(57) **CLAIM**

The ornamental design of footwear, as shown and described.

DESCRIPTION

FIG. 1 is a front perspective view of footwear according to a first embodiment;

FIG. 2 is a front elevation view of the footwear of FIG. 1;

FIG. 3 is a rear elevation view of the footwear of FIG. 1;

FIG. 4 is a top view of the footwear of FIG. 1;

FIG. 5 is a bottom view of the footwear of FIG. 1;

FIG. 6 is a left side view of the footwear of FIG. 1; and

FIG. 7 is a right side view of the footwear of FIG. 1.

FIG. 8 is a front perspective view of footwear according to a second embodiment;

FIG. 9 is a front elevation view of the footwear of FIG. 8;

FIG. 10 is a rear elevation view of the footwear of FIG. 8;

FIG. 11 is a top view of the footwear of FIG. 8;

FIG. 12 is a bottom view of the footwear of FIG. 8;

FIG. 13 is a left side view of the footwear of FIG. 8; and,

FIG. 14 is a right side view of the footwear of FIG. 8.

The broken lines shown in the drawings depict environmental subject matter and form no part of the claimed design.

1 Claim, 8 Drawing Sheets
